UNITED STATES PATENT OFFICE.

EUGENE W. HAWLEY, OF PHILADELPHIA, PENNSYLVANIA.

RETAINING DEVICE FOR GARMENT-SUPPORTERS.

1,178,919.

Specification of Letters Patent. Patented Apr. 11, 1916.

Application filed August 17, 1915. Serial No. 45,868.

To all whom it may concern:

Be it known that I, EUGENE W. HAWLEY, a citizen of the United States, residing at Philadelphia, county of Philadelphia, and 5 State of Pennsylvania, have invented a new and useful Improvement in Retaining Devices for Garment-Supporters, of which the following is a full, clear, and exact description, reference being had to the accompanying drawings, which form a part of this specification.

In wardrobe trunks, as is well known, there are usually provided extensible supporter rods extending forward from the rear 15 wall of the upright trunk, and extending between and resting upon these rods are hangers upon which the garments are hung. These hangers are slidable upon the rods of the supporter so as to permit access to the 20 garment hung upon any one of them without lifting the remaining hangers and their suspended garments from the rods.

It is rarely that a wardrobe trunk is filled to its capacity, but it is desirable that the 25 garments shall be pressed closely together so as to avoid sliding back and forth during transportation. Even when the trunk is quite full, the garments are held in close relationship only at their upper end portions, 30 the lower parts of the garments being swingable freely back and forth. It is therefore desirable to provide a device by means of which all the garments in the trunk, whether they are few or many, may be held pressed 35 firmly together throughout substantially their length and the mass of garments held against the rear of the trunk so that the garments may have little or no movement relatively to each other or to the trunk.

40 In the accompanying drawings, which show a preferred embodiment of an invention adapted to perform this function,—Figure 1 is a perspective view of the same applied to a wardrobe trunk. Fig. 2 is a 45 perspective view, partly in section, of one end of the main cross-bar of the retaining frame, the guide and ratchet bar and the locking pawl. Fig. 3 is a plan view of the 50 guide and ratchet bar at one side. Fig. 4 is an inside rear view of the same. Fig. 5

is a front view, partly broken away, of one end of the main cross-bar and locking pawl.

To the trunk *a* is applied a garment supporter of any kind. My retaining device being adapted to coöperate with any form of 55 supporter, the latter need not be described in detail and I have therefore shown a simplified supporter comprising two fixed tubes *b* secured to the rear wall of the trunk and extending parallel and close to the opposite end walls, and two rods *c* telescopically engaging the tubes *b*, whereby the supporter is rendered extensible. Garment hangers *d* extend between and rest upon the 60 two supporting members. Upon the hangers *d* the garments are suspended.

Extending horizontally along each side wall of the trunk, a substantial distance below the supporter and hanger, is a guide bar *e* having at opposite ends feet *e'* which are 70 riveted to the trunk wall and hold the bar fixed to and spaced therefrom. Extending between and secured to the feet of each guide bar is a ratchet bar *f*, which may be made of iron, steel, or vulcanized fiber. 75

A retaining frame is shown as composed of a metallic cross bar *g* and five wooden strips. Three of the strips, *h*, extend at right angles to the bar *g* and are secured 80 respectively near opposite ends and to the center thereof. The remaining two wooden strips, *i*, extend parallel to the cross bar and connect respectively the upper and lower ends of the strips *h*.

The cross-bar *g* is made of a metal plate 85 bent upon itself and is therefore of inverted U-shape in cross section. Each end of the bar *g* is cut away at *k* to provide a recess to embrace the guide-bar *e* and also to afford a space to clear the ratchet bar *f*. The feet 90 *e'* are narrower than the guide bars *e* so that the retaining frame may be applied to the guide bars *e* by slipping the cross bar onto the ends thereof.

Pivoted between its ends near each end, 95 and near the lower edge, of the cross bar *g* is a lever *m*, the outer shorter end whereof is cut away to approximately conform to the lower part of the cut away portion *k*, the projection at this end forming a pawl *n* 100

which is beveled to fit the teeth of the ratchet bar *f*. The opposite longer end of the lever *m* extends normally below the lower edge of the cross-bar *g* and is held in that position by a spring *o* confined between the walls of the cross-bar. The spring *o* is a single piece of wire bent in the shape of a bow, one end of which rests against the closed edge of the bar *g* while the other end 10 extends into a recess in the lever *m*. The spring *o* normally holds the lever *m* in the position shown in Fig. 5.

The retaining frame is slipped onto the ends of the guide bars *e* as above described 15 and may then be pushed toward the rear wall of the trunk until its movement is arrested by the garments suspended from the hangers. During this movement the pawls *n* click along the teeth of the ratchets *f*, the 20 springs *o* causing the pawl levers *m* to engage the successive ratchet teeth so that the retaining frame will remain locked in the position to which it is pushed and cannot be withdrawn without previously pressing up 25 the long ends of the levers *m*. Of course, in the rearward sliding movement of the frame, the long ends of the levers *m* may be lifted and the frame pushed back noiselessly. After 30 the frame is in retaining position it is as securely locked therein as if it were an integral part of the trunk.

The sliding fit of the cross bar *g* on the guide bars *e* is not so neat as to prevent a limited swinging movement of the retaining frame upon the guide bars, and therefore the retaining frame, when pushed home with force applied to top and bottom, will naturally assume the inclined position shown 35 in Figs. 1 and 2, thus holding the garments 40 tightly in place near their lower edges as well as at their upper portions. The release of the garments and the withdrawal and removal of the retaining frame are readily effected by taking hold of the frame 45 with both hands in such position that the long ends of the levers *m* are held upraised while the frame is moved out.

Having now fully described my invention, what I claim and desire to protect by Letters Patent is:

1. A retaining device for use in connection with garment supporters comprising a horizontal rearwardly-extending side guide-bar, a transversely-extending retaining frame, said frame including a horizontal cross-bar having parallel walls spaced apart, opposing parts of said walls being cut away at the end of the bar to form a hooked portion extending back of, and embracing, one 55 edge of the guide bar, a ratchet extending along the rear of the guide-bar, and a spring-pressed pawl lever pivoted on the retaining frame and extending between said walls and provided with a hooked end em-

bracing the other edge of the guide-bar and 65 engaging said ratchet.

2. A retaining device for use in connection with garment supporters, comprising a side guide bar, a retaining frame, slidable along the guide bar, a ratchet extending 70 along the guide bar, a pawl lever pivoted on the retaining frame and extending parallel therewith, and a spring normally holding the pawl lever in position to cause the same to operatively engage the ratchet and a part 75 thereof to project beyond one edge of the retaining frame, thereby enabling the retaining frame to be unlocked by merely grasping the same at the place of projection 80 of the pawl lever.

3. A retaining device for use in connection with garment supporters, comprising a side ratchet bar, a retaining frame slidable along 85 said bar, said frame including a cross-bar having parallel walls spaced apart, a pawl lever extending between the walls of the cross bar and pivoted thereto and having a manually operable end projecting beyond the open longitudinal edge of the cross-bar, and a spring normally holding said pawl 90 lever in operative engagement with the ratchet bar.

4. A retaining device for use in connection with garment supporters, comprising a side ratchet bar, a retaining frame slidable along 95 said bar, said frame including a cross-bar having parallel walls spaced apart, a pawl lever extending between the walls of the cross bar and pivoted thereto and having a manually operable end projecting beyond 100 the open longitudinal edge of the cross-bar, and a bow shaped wire spring extending between said lever and the closed longitudinal edge of the cross-bar and normally holding 105 said lever in operative relation with the ratchet bar.

5. A retaining device for use in connection with garment supporters, comprising side guide bars, feet extending from the ends of each guide bar at right angles 110 thereto and thence bent parallel thereto, whereby the guide bar may be held in fixed relation to the side wall of a trunk and spaced therefrom, a ratchet bar extending parallel to each guide bar and secured thereto, a cross-bar U-shaped in cross section and cut away at each end to embrace a longitudinal edge of the corresponding guide bar, a lever pivoted between its ends near each end of, and near the open longitudinal edge 115 of, the cross-bar and extending between the walls thereof, a pawl on the short end of each lever, the front foot of each guide bar being sufficiently narrower than the guide bar to allow the cross bar to slip endwise on 120 and off the same, a bow-shaped wire spring within the cross bar at each end thereof, one end of which spring rests against the 125

closed edge of the cross bar while the other end thereof extends into an orifice in the corresponding pawl lever, thereby normally holding its pawl in operative relation with the corresponding ratchet bar and holding its long end projected beyond the open longitudinal edge of the cross-bar, strips secured to and extending at right angles to

the cross-bar, and other strips extending parallel to the cross-bar and secured to the first strips.

In testimony of which invention I have hereunto set my hand, at Philadelphia, on this 9th day of August, 1915.

EUGENE W. HAWLEY.
